UNITED STATES PATENT OFFICE.

HENRY S. HOPPER, OF DETROIT, MICHIGAN.

CAR-BRAKE.

SPECIFICATION forming part of Letters Patent No. 393,561, dated November 27, 1888.

Application filed August 23, 1888. Serial No. 283,519. (No model.)

To all whom it may concern:

Be it known that I, HENRY S. HOPPER, a citizen of the United States, residing at Detroit, county of Wayne, State of Michigan, 5 have invented a certain new and useful Improvement in Car-Brakes; and I declare the following to be a full, clear, and exact description of the invention, such as will enable others skilled in the art to which it appertains to 10 make and use the same, reference being had to the accompanying drawings, which form a part of this specification, and in which—

Figure 1 is a view of the bottom of a car, showing trucks and my invention attached thereto. Fig. 2 represents a side elevation of 15 a section of a car-truck, illustrating another view of my invention. Fig. 3 is a rear elevation of an axle and wheels, showing the mode of attaching my invention to the axle, with 20 parts in section. Fig. 4 is a rear elevation with parts broken away.

This invention relates to that class of automatic brakes known as "momentum-brakes," in which the momentum of some moving part 25 set in motion by the movement of the car is utilized as the force to set the brakes.

My invention consists, essentially, in a fly-wheel journaled freely on a sleeve, which in turn loosely embraces an axle of the truck, 30 and both take up the motion of the axle. An adjacent spool adapted to wind upon itself a brake-chain is by the momentum of the fly-wheel brought into frictional engagement with the latter whenever the sleeve is checked, the 35 hub of the wheel being thereby caused to ride over a lateral cam at the end of its hub. The motion of the sleeve is checked by frictional shoes so engaged with the draw-bars that they brake the sleeve whenever there is an inward 40 pressure on either draw-bar and in a degree proportioned thereto; also, in the combination, with the foregoing, of a ratchet bar and pawl, the bar being engaged directly with the car-wheel brake-lever and adapted to hold the 45 brakes when set, and a light chain at the end of the bar, whereby it may be frailly connected with the adjacent car, so that should the train separate the chain, before severing, will set the brakes and the pawl hold them set; also, in 50 such a construction of the mechanism that it may be applied as an attachment to a car having the usual hand-wheel brake mechanism

and without impairing the latter or its usefulness.

In carrying out my invention, A is a car; 55 B, one of its axles; C C', its draw-bars; D D', its brake-beams; D², the brake-lever; D³, the brake-shoes; E E', respectively, its brake rod and chain, and E² the usual brake-staff and hand-wheel.

F is a fly-wheel journaled freely on a sleeve, G, and the latter loosely embraces the axle, so that when the car is in motion the sleeve and fly-wheel will take up the motion of the car. The hub of the wheel and the shoulder 65 g present cam-surfaces g' to each other, so that when the sleeve is checked the momentum of the fly-wheel, carrying it onward, causes one cam to ride up on the other and so shift the wheel lengthwise along the sleeve. 70

G' is a fixed collar.

H is a conical collar fixed to the axle and, with the conical end f of the hub of the fly-wheel, constitutes a double conical bearing.

I is a spool journaled loosely on said bearing. 75

J is a brake-chain, and J' a rod engaging the latter with the brake-lever D², so that when the chain is wound on the spool the brakes are set.

K is a lever swung from its top.

K' is a similar lever pivoted at k to a link, k', which is in turn swung from its top.

k" is a connecting-spring, and K² represents friction-shoes which embrace the loose sleeve 85 G. A rod, L, is adjustably engaged with the lever K'. It connects the latter with the end of a lever, M, which is in turn united with the draw-bar, as shown, so that a thrust upon the draw-bar forces the top of the lever K' toward 90 the axle, sets the friction-shoes K², and checks the sleeve G.

L' is another rod engaging the same lever K', and, extending to the opposite end of the car, is fastened to a lever, M', as shown, and 95 the latter is united to the adjacent draw-bar C', so that a thrust on the latter likewise operates to set the friction-shoes K². The lever M' is engaged with the rod L' in such a way that should the train break in two at this point 100 the frail chain N² before it severs will draw upon the rod L' and set the brakes, while at the same time the connection at m will give way, so that the lever may not be broken nor

the chain be required to overcome the resistance of the draw-bar spring in setting the brakes. I would ordinarily simply seat the lever in a squared recess in the end of the rod 5 L', or make some other easily separable connection of the two parts.

N is a ratchet-bar connected with the brake-lever D'.

n is a pawl adapted when the bar N is moved 10 forward in the setting of the brakes to hold it in that position.

N' is a light chain that may be engaged with the adjacent car, so that should the train break in two the chain before severing will set the 15 brakes and the pawl hold them set. The pawl may be engaged with a rod, n', projecting to the side of the car, whereby it may be disengaged at will, and a ball, n², may, when thrown beyond its upright position, serve to hold the 20 pawl disengaged—a matter desirable when making up trains or switching about the yard. The levers M M' serve to trip the pawl when either draw-bar is pulled.

I' is a supporting-arm for the spool. It 25 springs toward the fly-wheel just enough to hold the latter engaged with the cams g', but not enough to make a frictional contact between the spool and wheel sufficient to revolve the spool.

30 The operation will now be understood. When the train is being pulled in either direction, the sleeve and fly-wheel take up the motion of the car. Now, coming to a downgrade, the speed is checked at the locomotive 35 and the draw-bars are thrust inward. This thrust cramps the friction-shoes K² against the sleeve G, checking its motion. The fly-wheel by its momentum continues onward, and the cams g' thrust the fly-wheel toward the spool 40 I, clamping it between the conical heads which constitute its bearing, the chain J is wound upon it, and the brakes are set. The friction which holds the spool is due solely to the bearing of the shoes K², and this is proportioned to the thrust on the draw-bar, being 45 light when the engineer is simply checking the speed and strong when he seeks to stop suddenly. The pawl holds the brakes set, but the slightest pull on the draw-bar causes the lever 50 M to trip the pawl, and the friction-shoes K² are simultaneously released from the sleeve G.

If the train stands at rest and backs from a 55 standing position, the shoes K² are set at once and the sleeve G and fly-wheel are held against revolving, and the car-brakes therefore remain off. So, also, if the brakes are set by stopping the train, and it is desired to back, the brakes may be first released by a slight start forward. The ordinary brake-wheels 60 may be employed, when desired, and by employing a distinctive wheel a brakeman on the train may at once see which cars have the automatic brakes.

Any car provided with the apparatus is complete in itself and may be coupled into any 65 train, taking care of its own brakes, regardless of the other cars or of the brakeman.

What I claim is—

1. The automatic momentum-brake mechanism, consisting of the combination, with the 70 draw-bar and brake-lever, of a fly-wheel journaled freely on a sleeve which loosely embraces the axle, an adjacent spool having a chain engaging it with the brake-lever, friction mechanism adapted by the thrust of the draw-bar to engage the sleeve, and a cam on the sleeve, whereby the fly-wheel is shifted into frictional engagement with the spool and its momentum utilized to set the brakes, substantially as described. 75

2. In an automatic brake mechanism, the combination, with the brakes and a ratchet rod and pawl adapted to hold the brakes when set, of a rod connected with the draw-bar and arranged so as to trip the pawl and release the 80 brakes when the car is started, substantially as set forth.

3. On a freight-car, the combination, with the automatic momentum mechanism for setting the brakes and a ratchet rod and pawl for 85 holding them, of means for holding the pawl disengaged when desired, substantially as described. 90

4. In an automatic momentum-brake, the combination, with the spool, the fly-wheel, and 95 sleeve provided with engaging cam-faces g', of brake-shoes adapted to engage the sleeve and retard its motion, the construction being such that by the onward movement of the fly-wheel the cams will shift the wheel into frictional engagement with the spool, substantially as described. 100

5. In an automatic momentum-brake, the combination, with the fly-wheel, the sleeve provided with engaging cam-faces g', the shoes 105 adapted to retard the motion of the sleeve, and the spool adapted when revolved to set the brakes, of a supporting-arm, I', adapted to give the spool a slight lateral pressure against the fly-wheel, substantially as described. 110

6. In an automatic momentum-brake, the combination, with the spool, the fly-wheel, the sleeve provided with cam-faces g', and the shoes adapted to retard the motion of the 115 sleeve, of a lever or levers adapted to support the shoes adjacent to the sleeve, substantially as described.

7. In an automatic momentum-brake, the combination, with the spool, the fly-wheel, the 120 sleeve provided with cam-faces g', the shoes adapted to retard the motion of the sleeve, and the supporting-levers K K', of a supporting-link, k', and a connecting-spring, k², adapted to give the levers a simultaneous lateral motion, substantially as described. 125

8. In an automatic momentum-brake, the combination, with the friction-shoes and their supports, of the rod L', extending to the opposite end of the car, and in connection therewith the draw-bar C' and lever M', whereby a thrust upon this draw-bar will operate to set the brakes, substantially as described. 130

9. In an automatic momentum-brake, the

combination, with the brake mechanism and rod L', of the lever M' and frail chain N², the said lever and rod united at m by an engagement adapted to readily separate when the 5 chain is strained, substantially as described.

10. In an automatic momentum-brake, the combination, with the friction-shoes, their supports, and the pawl and ratchet, of the rod L', extending to the opposite end of the car, 10 and in connection therewith the draw-bar C'

and lever M', whereby a thrust on this draw-bar will set and hold the brakes and a draft upon it will trip the pawl and release the brakes, substantially as described.

In testimony whereof I sign this specification 15 in the presence of two witnesses.

HENRY S. HOPPER.
